UNITED STATES PATENT OFFICE.

JOHN J. HENNESSEY, OF MILWAUKEE, WISCONSIN.

ADJUSTABLE SIDE BEARING.

1,222,951.

Specification of Letters Patent. Patented Apr. 17, 1917.

Application filed April 17, 1916. Serial No. 91,592.

To all whom it may concern:

Be it known that I, JOHN J. HENNESSEY, a citizen of the United States, residing at Milwaukee, in the county of Milwaukee and State of Wisconsin, have invented a certain new and useful Improvement in Adjustable Side Bearings, of which the following is a full, clear, concise, and exact description, reference being had to the accompanying drawings, forming a part of this specification.

This invention relates to improvements in adjustable side bearing.

The object of the invention is to provide a rocker side bearing adapted for use on railway cars and so arranged that adjustment may be obtained in accordance with the spacing between the car bolsters.

Another and more specific object of the invention is to provide a gravity rocker side bearing employing a horizontal reciprocating top plate and having means to adjust the height of the top plate relatively to the base member of the side bearing.

The invention furthermore consists in the improvements in the parts and devices and in the novel combinations of the parts and devices herein shown, described or claimed.

In the drawing forming a part of this specification, Figure 1 is an end elevation of portions of a body and truck bolster showing my improvements in connection therewith. Fig. 2 is a vertical sectional view of the improved side bearing and taken substantially on the line 2—2 of Fig. 1, the section being upon an enlarged scale. Figs. 3 and 4 are transverse, vertical sectional views of the side bearing taken on the lines 3—3 and 4—4 respectively of Fig. 2.

In said drawing, 10 denotes a body bolster which is pivotally connected at the center to the truck bolster 11 in the usual manner, the body bolster being provided with a striking plate 12 which co-operates with my improved side bearing designated generally by the reference A and which is mounted on the truck bolster.

The improved side bearing A comprises broadly a base casting B, a top plate C, a bottom plate D, a pair of rockers E—E and a spring F, together with various details of construction co-operating therewith, as hereinafter described.

The base casting B is provided with a flat bottom 13 adapted to be riveted to a bolster, said casting B having a pair of upstanding

side walls 14—14, said walls 14 on their inner faces being provided with a longitudinally extending series of tongues and grooves 15. The bottom plate D is of substantially U-shape in cross section as appears from Fig. 3, said member D having a lower wall 16 and side walls 17—17, the latter on their outer faces being provided with a series of tongues and grooves 18—18 which co-operate with the tongues and grooves 15 on the base casting. The upper surface of the lower wall 16 is convex as indicated at 19 and forms bearings for the rockers, the peripheries of which are concave as indicated at 20. Each of the rockers E, on its lower periphery is provided with a series of recesses 21, which co-operate with a corresponding series of bosses 22 on the member D, to thereby retain the rockers in proper position. The bottom plate D is provided at its center with a transversely extending limiting wall 23 having bosses 24 on each side thereof at the center, the rockers being limited in their movement by engagement with said wall, the rockers being provided with grooves 25 on both sides, see Fig. 2, which fit the bosses 24. At their upper ends, each of the rockers E is provided with a cylindrical knob 26 which fits a correspondingly shaped bearing 27 formed on the under side of the top plate C. To retain the top plate C in normal position and return it to such position after each actuation of the same, the spring F is attached thereto as indicated at 28, the opposite end of said spring being attached to an eye bolt 29, which passes through a suitable perforation in the wall 23, the lower end of the bolt being provided with a nut 30 seated in a countersink 31 in the under side of the lower plate D. On each side of the plate C, the side walls thereof are provided with outwardly extending lugs 32 and 33 between which is seated the upper flange 34 of a retaining plate 35, the retaining plate 35 extending downwardly and having an in-turned lower flange 36 which extends under an outwardly extended flange 37 along the top of the corresponding side wall of the bottom plate D. The retaining plates 35 are detachably held in position by any suitable means such as the cotters 38.

As clearly appears from Figs. 1 and 2, the base casting B is provided at each end thereof with an outwardly extended pair of perforated ears 39—39, through which passes

a transversely extending bolt 40. By this means, longitudinal movement of the bottom plate D relatively to the base casting B is prevented so long as the bolts 40 remain in position. To permit the escape of dirt or other foreign matter which may accumulate in the bearing, the side walls 14 are cut away as indicated at 41 and the side walls of the plate D are similarly cut away as indicated 10 at 42.

In operation, it is apparent that the top plate C will reciprocate longitudinally when the bolsters approach each other and have relative radial movement, the amount of 15 movement of the plate C being limited by the engagement of one of the rockers E with the limiting wall 23.

Upon release of the pressure on the top plate C, the latter will be returned to normal position by means of the spring F. Accidental lifting or removal of the top plate C from the bottom plate D is prevented by the retaining plates 35 which, of course, operate in conjunction with the spring F.

25 The parts as shown in the drawing represent the top surface of the plate C in its lowermost position, but in order to increase the height of the upper surface of said plate C relatively to the base casting B, the bolts 40 are withdrawn, after which the top plate C, rockers E, and bottom plate D are removed as a unit by sliding the same lengthwise of the base casting B. The members C, D and E may then be replaced in a higher position 30 by engaging the tongues and grooves of the member D at higher points in the tongues and grooves of the side walls 14 of the base casting. The parts are then locked in position by replacing the bolts 40. As will be 35 understood from the foregoing, various adjustments may be made depending upon the relative positions in which the bottom plate D and base casting B are assembled and a change may be very easily made without disturbing the rockers or the mounting thereof 40 between the members B and C.

45 Although I have herein shown and described what I now consider the preferred embodiment of my invention, the same is merely illustrative and I contemplate all changes and modifications that come within the scope of the claims appended hereto.

I claim:

1. In a rocker side bearing, the combination 50 with a base member, of a top plate, rockers located between said top plate and base member, and means for adjusting said

top plate and rockers as a unit and without disturbing the relation therebetween, vertically relatively to said base member. 60

2. In a side bearing, the combination with a base casting, of a horizontally reciprocating top plate, a plurality of members interposed between said top plate and base casting, and means for adjusting said top plate and members vertically, as a unit and without disturbing the relation therebetween, relatively to said base casting. 65

3. In a side bearing, the combination with a base casting, of a top plate, a bottom plate, 70 rockers interposed between said top and bottom plates, and means permitting adjustment of said bottom plate, top plate, and rockers as a unit and without disturbing the relation therebetween, vertically relatively to 75 the base casting.

4. In a side bearing, the combination with a base casting having upstanding, spaced side walls, of a bottom plate slidably mounted between the side walls of the base casting, 80 a reciprocating top plate, rockers interposed between said top and bottom plates, and detachable means at the ends of said base casting for retaining said bottom plates and the parts mounted thereon, in operative position. 85

5. In a side bearing, the combination with a base casting and a bottom plate relatively vertically adjustable, of a reciprocating top plate, rockers interposed between said top and bottom plates, and a spring connected 90 to said top and bottom plates adapted to return the top plate to normal position after each actuation thereof.

6. In a side bearing, the combination with a base casting having upstanding, spaced 95 side walls provided with longitudinally extending tongues and grooves on their inner faces, of a bottom plate, the side walls of which are provided with longitudinally extending tongues and grooves coöperable with 100 those of said base casting, transversely extending bolts mounted in said base casting at the ends thereof and adapted to prevent removal of said bottom plate from the base casting, a reciprocating top plate, and a plurality of rolling members interposed between 105 said top and bottom plates.

In witness that I claim the foregoing I have hereunto subscribed my name this 1st day of April 1916.

JOHN J. HENNESSEY.
